EGG-CUP

Alexander Yelin, Brussels, Belgium

Application November 30, 1955, Serial No. 39,091

Term of patent 14 years

(Cl. D44—9)

FIG. 2

Fig. 1 is a perspective view of an egg-cup showing my new design.

Fig. 2 is a view in rear elevation.

Fig. 3 is a view in side elevation.

I claim:

The ornamental design for an egg-cup, as shown.
